RIVET FEEDING DEVICE

William R. Kovacs, Cleveland, Ohio, assignor to
 The Cleveland Pneumatic Tool Company,
 Cleveland, Ohio, a corporation of Ohio

Application September 15, 1943, Serial No. 502,482

4 Claims. (Cl. 78—46)

The present invention relates to improvements in devices for manually inserting rivets or the like into work openings, and more particularly to a device for delivering rivets from one end thereof.

The primary object of the invention resides in the provision of a rivet feeding device embodying improved means for releasably holding a plurality of rivets in position to be individually discharged from the delivery end of the device.

Another object of the invention is to provide a rivet feeding device including a barrel adapted to contain a plurality of axially disposed rivets and means on the delivery end of the barrel which permits the discharge of the innermost rivet and at the same time will grip the next adjacent rivet to preclude its premature discharge from the barrel.

A further object of the invention is to provide an improved device of the above character in which resilient fingers are employed for retaining the rivets in the barrel and means engaging said fingers for holding them in rivet engaging position to preclude the discharge of the end rivet from the barrel until said device is in the desired position for releasing a rivet.

A still further object of the invention is to provide an improved device of the character mentioned in which the barrel and a thrust member or nose piece engageable with the work are relatively movable for permitting the resilient fingers to spread, and in which the thrust member is of a form such that it is not likely to cause marring of the work.

Other objects and advantages more or less ancillary to the foregoing reside in the specific construction and aggroupment of the elements peculiar to this structure, as will become apparent from a more complete examination of this specification.

In the drawings which illustrate the invention:

Fig. 1 is a perspective view illustrating a rivet placing device embodying the features of the present invention.

Fig. 2 is a side elevational view thereof partly in section.

Fig. 3 is an end view.

Fig. 4 is a fragmentary vertical sectional view taken substantially on line 4—4 of Fig. 3.

Fig. 5 is a fragmentary vertical sectional view of a modified form of the invention.

Fig. 6 is a perspective view on a larger scale showing in detail rivet gripping fingers employed in connection with the invention.

Fig. 7 is an end view showing the fingers forced inwardly into gripping position by an encircling tubular member.

Fig. 8 is a view similar to Fig. 6 showing the corresponding parts employed in the Fig. 5 modification, and

Fig. 9 is an end view of the Fig. 8 construction with a confining tubular member in finger restraining position.

10 Referring to the drawings for a more detailed description thereof, and particularly Figs. 1 to 4, inclusive, which illustrate one embodiment of the invention, the improved rivet feeding or placing device is generally designated by the reference numeral 10 and includes a barrel 11 which forms a support or magazine adapted to contain a plurality of rivets 12 or other articles to be fed. The barrel 11 is open at both ends thereof and is fabricated with a longitudinal slot 13 in the wall thereof. A plunger 14 is adapted to be inserted through the open outer end 15 of the barrel for engagement with the outer end of a series of rivets previously placed in the tube as shown in Fig. 4, said plunger being formed with a lug 16 which projects through the slot 13 and is movable therewith. A tension spring 17 is connected to the lug 16 as indicated at 18 and constantly applies a pulling force to the plunger 14, causing the latter to advance the rivets 12 along the barrel 11 toward the inner or delivery end 11' thereof.

Soldered or otherwise fixedly mounted on the inner or delivery end 11' of the barrel 11 is a bracket 19, which includes a sleeve portion 20 surrounding or partially surrounding the barrel and a pair of spaced ears B projecting substantially radially of the barrel. The ears B form a support for an elongated substantially U-shaped cover 21 which is adapted to be releasably held in closed position adjacent the barrel 11 by a spring clip 22 which is carried by the cover and engageable with the barrel adjacent its outer end. The cover 21 is pivotally connected to the ears B by means of a transverse pin 23 which permits the cover to be swung toward or away from the barrel 11 during the loading of the barrel with rivets or the like. Between the ears B there is provided a grooved roller 24 which is rotatably mounted on the pivot pin 23 and around which extends the tension spring 17, said tension spring extending longitudinally within the cover 21 and having its outer end suitably anchored thereto by means of a lug or the like 25.

A sleeve 26 is permanently secured to the inner 55 or delivery end 11' of the barrel 11, said sleeve

being formed with a plurality of resilient fingers 27 adapted to be urged into clamping engagement with the innermost rivet 30 supported within the barrel 11. The inner or free ends 28 of the resilient fingers 27 are convexed and normally flex outwardly away from the axis of the barrel 11 and unless restrained would permit uninterrupted discharge of the rivets from the barrel. The confining or restraining means for the fingers comprises a tubular member 29 which surrounds the sleeve 26 and fingers 27 and is axially movable relative to the barrel 11. The outer end of the member 29 is formed with a lug 31 which is disposed within the slot 13 for preventing rotation of said member relative to the barrel 11. The normal position of the member 29 is shown in Figs. 1 and 2 of the drawings, and it will be noted that the innermost end of said member has bearing engagement with the finger ends 28 so as to urge said ends inwardly for clamping engagement with the head of the innermost rivet 30. While the normal tendency of the spring fingers 27 is to flex outwardly, the tube 29 brings sufficient pressure to bear on the finger ends to cause the latter to firmly grip the innermost rivet head and thereby preclude its discharge from the barrel 11. However, as will hereinafter appear, the barrel 11 and sleeve 26 are moved longitudinally relative to the member 29 to free the ends 28 from said member whereupon they expand and allow the innermost rivet to be ejected.

In addition to the series of fingers 27, the sleeve 26 is also formed with a pair of diametrically opposed resilient fingers 32 which are shorter than the fingers 27. The fingers 32 are adapted to extend through diametrically opposed slots 33 formed in the delivery end of the barrel 11 and function to prevent the escape of the rivet next adjacent the innermost rivet being ejected. As shown in Fig. 4 of the drawings, the innermost rivet has just been released from the fingers 27 and has entered the opening 34 within the work 35 and simultaneously with the release of the rivet, the fingers 32 are urged inwardly by the tubular member 29 for engagement with the head of the next adjacent rivet 36. The fingers 32 are similar in construction to the fingers 27 in that they normally flex outwardly away from the axis of the barrel 11. In order to urge the short fingers 32 into clamping engagement with the head of the rivet 36, the end of the tubular member 29 is formed with diametrically opposed downwardly extending lips 37 which are positioned directly above the fingers 32. When the tubular member 29 is in the position shown in Fig. 2 of the drawings, the lips 37 are out of bearing engagement with the fingers 32, and said fingers are thereby free to flex outwardly away from the rivets. As before indicated, at that time the fingers 28 are urged into gripping engagement with the head of the innermost rivet 30. However, as the barrel 11 is moved longitudinally relative to the tubular member 29 to the position shown in Fig. 4 of the drawings, the lips 37 will bear against the fingers 32 to urge said fingers inwardly for gripping the head of the next adjacent rivet 36. This action is simultaneous with the release of the innermost rivet 30, and it will be seen that only one rivet at a time is thereby permitted to be freed from the delivery end of the tube.

A coil spring 38 is interposed between the bracket sleeve 20 and the outer end of the tubular member 29. The bracket 19 being fixedly secured to the barrel 11 will move with said barrel against the resistance of the spring 38, while a

rivet is being ejected and said spring functions to return the barrel and bracket to normal position when the device is removed from the work 35.

5 A pair of arms 39 are secured to and extend forwardly of the tubular member 29 and are adapted to engage the surface of the work 35 for holding the free ends of the resilient fingers 27 in spaced relation to the work. Thus the resilient fingers are free to flex outwardly as the tube is moved toward the work without scraping on the work surface. The arms 39 are formed with laterally extending feet 40 which engage the surface of the work without marring or otherwise damaging the same.

10 It will be seen from the foregoing description that when the barrel 11 has been charged with a series of rivets 12 and they are subjected to feeding pressure by the plunger 14, the head of the innermost rivet 30 will be engaged by the inwardly pressed ends of the resilient fingers 27, and said rivet will be held with the stem thereof projecting from the tip of the device ready to be inserted into the opening 34 of the work 35, as shown in Fig. 2. When inserting the stem of the rivet 30 into the opening 34, the feet 40 will be brought into bearing engagement with the surface of the work 35, whereupon the barrel 11 is shifted toward the work by sliding movement within the tubular member 29, moving the ends 28 of the fingers 27 out of engagement with the tubular member 29 and simultaneously causing the lips 37 to depress the fingers 32. As the ends 28 are released from the tubular member 29, the fingers 27 will flex outwardly and the rivet 30 will be projected or snapped into the work opening by the action of the spring 17. Thereupon, the barrel 11 is released, and under the action of the spring 38 will be moved rearwardly relative to the tubular member 29 so that the fingers 32 will be freed from the lips 37 to allow the next adjacent rivet 36 to move forwardly when it will be gripped by the ends 28 which have been flexed inwardly by the tubular member 29. This action is repeated until all of the rivets have been exhausted from the barrel and when it is desired to reload the barrel with an additional supply of rivets, the plunger 14 is removed through the open end 15 by stretching the spring 17 and after loading, the plunger is again positioned in abutting relation with the head of the end rivet.

15 The form of the invention shown in Fig. 5 differs from the previously described form by omitting the pair of short fingers and the depressing lips formed on the tubular member for urging those fingers inwardly. In this form the construction of the barrel 11, plunger 14 and spring 17 is the same as the preferred form. A sleeve 126 is permanently secured to the inner or delivery end of the barrel 11 and said sleeve is formed with a plurality of resilient fingers 127 having convexed ends 128 adapted to be urged into clamping engagement with the innermost rivet 130. The ends 128 are urged inwardly into rivet clamping engagement by the tubular member 129 which is mounted on the barrel 11 in finger surrounding position and is slideable relative to said barrel. By shifting the barrel 11 toward the work 135, the ends 128 will be free to flex outwardly to release the innermost rivet 130 into the opening 134. As the device is moved away from the work 135, the fingers are urged inwardly by contact with the member 129 to clamp the next adjacent rivet 136. It will thus be seen that the action of the two forms is simi-

lar insofar as restraining the innermost rivet is concerned but that the modified form dispenses with the means for preventing escape of the rivet next adjacent to the innermost rivet.

Although the foregoing description is necessarily of a detailed character, in order to completely set forth the invention, it is to be understood that the specific terminology is not intended to be restrictive or confining and it is to be further understood that various rearrangements of parts and modifications of structural detail may be resorted to without departing from the scope or spirit of the invention as herein claimed.

I claim:

1. In a device for holding and delivering rivets or the like, a barrel forming a magazine for a plurality of rivets, means for urging the rivets toward the delivery end of the barrel, resilient fingers carried by the barrel tending to flex outwardly, a member carried by but movable axially upon the barrel normally urging said fingers inwardly for holding them in rivet engaging position, said member being adapted to abut against the work and to move relatively to the barrel in an axial direction when the barrel is moved toward the work in order to release the fingers from the control of said member.

2. In a device for holding and delivering rivets or the like, a barrel forming a magazine for a plurality of rivets, means for urging the rivets toward the delivery end of the barrel, resilient fingers carried by the barrel tending to flex outwardly, a tubular member surrounding the barrel and movable axially thereupon, said tubular member normally confining said fingers for holding them in rivet engaging position, said tubular

member being adapted to abut the work and to move relatively to the barrel in an axial direction when the barrel is moved toward the work and thereupon to release the fingers and permit them to expand for discharging a rivet.

3. In a device for holding and delivering rivets or the like, a barrel forming a magazine for a plurality of rivets, means for urging the rivets toward the delivery end of the barrel, two sets of fingers carried by the barrel and spaced apart axially, one set for engagement with the endmost rivet and the other for engagement with the next adjacent rivet, means movable relatively to the barrel for abutting the work when the barrel is moved toward the work, said means being adapted upon such relative movement to release the endmost rivet and grip the next adjacent rivet.

4. In a device for holding and delivering rivets or the like, a barrel forming a magazine for a plurality of rivets, means for urging the rivets toward the delivery end of the barrel, two sets of fingers carried by the barrel and spaced apart axially, the fingers of both sets tending to flex outwardly, a tubular member surrounding the barrel movable axially thereupon, said tubular member normally confining one set of fingers to cause them to retain the end rivet while leaving the other set free to expand, said tubular member being adapted to abut the work and to move relatively to the barrel in an axial direction when the barrel is moved toward the work and thereby to release the fingers holding the end rivet, said tubular member having means which is effective at the same time for confining the other set of fingers to cause them to grip the next adjacent rivet.

WILLIAM R. KOVACS.
